UNITED STATES PATENT OFFICE.

JOHN H. MILLER, OF MACDUNN, WEST VIRGINIA.

COAL-LOADING APPARATUS.

1,411,928.

Specification of Letters Patent. Patented Apr. 4, 1922.

Application filed November 16, 1920. Serial No. 424,399.

To all whom it may concern:

Be it known that I, JOHN H. MILLER, a citizen of the United States, residing at MacDunn, in the county of Fayette and State of West Virginia, have invented new and useful Improvements in Coal-Loading Apparatus, of which the following is a specification.

This invention relates to means for loading railway cars, trucks, wagons and the like and is especially designed for loading coal cars at the mine.

An object of the invention is the provision of means whereby the transfer of coal from the mine dump to railway cars is facilitated, the said invention including a power operated shovel or scoop, which takes up coal and transfers it from the dump to the cars.

Another object is the provision of means for automatically "throwing off" the drag cable of the scoop from the guide pulley, both in the forward and return movement of the said scoop.

A further object is the provision of a novel form of scoop which will dig into and gather its load and carry the same to the cars with a minimum amount of power.

With the above and other objects in view, the invention further includes the following novel features and details of construction, to be hereinafter more fully described, illustrated in the accompanying drawings and pointed out in the appended claims.

In the drawings:

Figure 1 is a plan view of a loading mechanism constructed in accordance with the invention.

Figure 2 is an enlarged detail plan view of the loading scoop.

Figure 3 is a side elevation of the same.

Figure 4 is a central longitudinal sectional view.

Figure 5 is an enlarged side elevation of the throw-off pulley and a portion of the drag cable, the latter being in a position just prior to the throw-off operation.

Figure 6 is a view similar to Figure 5 showing the cable about to leave the throw-off pulley.

Referring in detail to the drawings, where like characters of reference denote corresponding parts, the reference character M, indicates a portion of a main track which is located adjacent a mine coal dump indicated at D, the latter being located within

an enclosure bounded by a wall or fence W. The dump enclosure is open as indicated at O and extending from this opening is an inclined chute S, which has suitably secured at one end an extention E, which is adapted to be moved into position to bridge the space between the end of the chute S and the railway car R. All of the foregoing may be of the usual or any preferred arrangement.

Located upon the side of the track opposite the dump D and in a line with the chute S is a spur track indicated at 10. This track is designed to accommodate the operating mechanism which is mounted upon a wheel supported platform or car 11. This car may be operated upon the main track M and transferred to the spur track 10 by means of a turn table 13 of any approved construction.

Mounted upon the car 11 is an engine, preferably of the hoisting type as shown at 14. This engine is designed to operate a plurality of drums 15, 16 and 17, the latter being freely mounted upon their shafts and adapted to be connected to the latter by means of clutches 18. The drum shafts are connected by a gear train 19 which is driven from the engine 14, the gearing between the drums 15 and 16 being arranged to provide for their rotation in opposite directions.

Wound upon the drum 15 is an inhaul drag cable 24, which is connected to a scoop 25 and which passes over a throw-off guide pulley 26. Also connected to the scoop 25 is an inhaul drag cable 27, which passes around guide pulleys 28 and is wound upon the drum 16. Thus, when the drums are rotated in one direction the cable 24 will operate to pull the scoop inward or toward the car 11 and when the drums are rotated in an opposite direction, the cable 27 will operate to pull the scoop outward or away from the car 11, the cable 24 being simultaneously paid out.

The scoop 25 which is shown in detail in Figures 2, 3 and 4, comprises a bottom 29 and side walls 30, which converge at one end to provide a rear wall 31, to which one end of the cable 27 is secured. The opposite end of the scoop is provided with a flared mouth, while the forward edge of the bottom 29 is curved downwardly as indicated at 32 so as to exert a digging action and force the coal or other material within the body of the scoop as the latter is dragged along. The forward edge of the bottom 29

has extensions upon either side as indicated at 33, the said extensions curving upward and forward as shown in Figure 4. This prevents the edge 32 from digging too deeply into the coal and thus facilitates the movement of the scoop.

The cable 24 is connected to the scoop through the medium of a bail 34, whose ends are pivoted to the sides of the scoop as shown at 35. The forward ends of the sides are connected by an arch 36, which may be used as a handle if desired.

By reference to Figure 1 of the drawings it will be apparent that in order to move the scoop from the position shown over the chute S to the car R, it will be necessary to disengage the cable 24 from the guide pulley 26 and one of the novel features of the invention resides in the provision of means for automatically accomplishing this operation. For this purpose the cable 24 carries an obstruction or button 37 and the pulley 26 has one of its flanges provided with a number of flattened portions 38, whereby the depth of the pulley groove will be reduced at these points. The groove of this pulley is designed to accommodate the cable 24 and as the diameter of the button 37 is greater, when this button reaches the pulley it will cause the cable to ride upward from the groove and as the depth of the latter has been reduced by cutting away or flattening the pulley flange, the cable will be automatically thrown off or disengaged from the pulley so that the scoop 25 may move over the chute to the car R. After the scoop has dumped its load it is drawn outward or away from the car by engaging the cable 27 over the pulley 26, the cable 27 is also provided with a button 37 so as to be automatically thrown off the said pulley. As soon as the scoop and the other button 37 passes the pulley 26, the cable is reengaged with the said pulley.

Wound upon the drum 17 is a cable 39, 45 which passes over guide pulleys 40 and is connected to the car R as indicated at 41. Thus, when the car R is loaded it may be moved along the track for connection with the train and make room for an empty car. 50

If desired, the wheels of the car 11 may be so mounted upon their axles as to permit of relative lateral adjustment so as to adapt the car for use upon different gauge tracks.

The invention is susceptible of various 55 changes in its form, proportions and minor details of construction and the right is herein reserved to make such changes as properly fall within the scope of the appended claims. 60

Having described the invention what is claimed is:—

1. In a loading mechanism, the combination with a source of power, a cable operated scoop, means for guiding the scoop in a direction at right angles to the line of pull, of a pulley provided with an interrupted flange and included in said guiding means and means carried by the cable and co-operating with the pulley for automatically disengaging said cable from the pulley. 65

2. In a loading mechanism, the combination with a source of power, a cable operated scoop and means for guiding the scoop in a direction at right angles to the line of pull, 70 of a pulley included in said guiding means, said pulley being grooved and having its flange upon one side of the groove formed with a plurality of flattened portions to reduce the depth of said groove and means 75 carried by the cable to provide an enlarged portion, whereby the cable will be automatically thrown off the pulley when the enlarged portion reaches a reduced portion of the groove. 80

In testimony whereof I affix my signature.

JOHN H. MILLER.
